EXCAVATOR TOOTH TIP

Harry H. Smedley, Oakland, Calif.

Application March 11, 1957, Serial No. 45,180

Term of patent 14 years

(Cl. D39—1)

Fig. 1.

Fig. 2.

Fig. 3.

Figure 1 is a top perspective view of the excavator tooth tip showing my new design;

Figure 2 is a bottom plan view thereof; and

Figure 3 is a side elevational view thereof.

I claim:

The ornamental design for an excavator tooth tip, substantially as shown.
